FIG. IV

FIG. V

FIG. VIII.

INVENTOR:

DANIEL J. DUNBAR,

by *Arthur E. Paige*,
Attorney.

UNITED STATES PATENT OFFICE

DANIEL J. DUNBAR, OF PHILADELPHIA, PENNSYLVANIA

WINDOW

Application filed September 12, 1928. Serial No. 305,407.

As hereinafter described, my invention may be employed with particular advantage in what are known as double-hung windows, altho not limited to windows of that type. It is an object and effect of my invention to provide weathering strips, preferably of spring metal, to render the joints between the sash and the frame weather-proof; such weathering strips being preferably rigidly connected with the sash frames at one edge and having free edges in sliding contact with a portion of the window frame, preferably the parting strip between the sashes in a double-hung window. A further object and effect of my invention is to substitute for the ordinary counter-balance sash weights and cords, springs which are coiled in the window frame and have means connecting them with the sash, preferably tape-like strips of flexible metal respectively engaged with weathering strips upon opposite sides of the sash. As hereinafter described, the springs are provided with metal housings mounted in the opposite jambs of the window frame and in such relation therewith that the springs may be removed and replaced without removal of the sash from the window frame. My invention also includes anti-rattling devices in the window frame including sheet metal springs each adapted to frictionally engage two sashes. An adjunctive feature of my invention is the formation of the window sashes in separable parts respectively fitting in sliding engagement with the window frame and holding the glass or other closure. The latter feature of construction and arrangement is advantageous in that it permits the interchange of sash frame parts which are respectively glazed and provided with insect screening, without removal from the window frame of the parts of the sash which are in sliding engagement therewith.

My invention includes the various novel features of construction and arrangement hereinafter more definitely specified.

In said drawings; Fig. I is an inside elevation of a double-hung window, conveniently embodying my improvements.

Fig. II is a fragmentary plan sectional

view of said structure, taken on the line II, II in Fig. I, but on a larger scale.

Fig. III is a fragmentary plan sectional view of said structure, taken on the line III, III in Fig. I, but on a larger scale. 55

Fig. IV is a fragmentary elevation of the inner face of the window jamb shown in section in Figs. II and III.

Fig. V is a fragmentary vertical sectional view, taken on the line V, V in Figs. I, II 60 and III.

Fig. VI is a fragmentary perspective view of a piece of one of the outer separable sash stiles shown in Fig. I, which is adapted to 65 slide in the jamb.

Fig. VII is a fragmentary perspective view of a piece of one of the inner sash frames shown in Fig. I, which is normally detachably secured in rigid relation with the outer stile shown in Fig. VI. Fig. VIII shows a 70 modified form of inner sash frame.

In said figures; the window frame 1 is composed of the lintel 2, opposite jambs 3 and sill 4. Said frame jambs each have a parting strip 6 between the inner molding 7 and the outer molding 8 and forming slide-ways 9 and 10 for the double-hung sashes 12 and 13. 75

Each of said sash 12 and 13 has, upon opposite sides thereof, oppositely counterpart weathering strips 15, conveniently rigidly connected therewith, at one edge, by screws 16, if the sash is formed of wood as indicated. However, such weathering strips may be otherwise secured upon sash frames which are formed of metal. Said weathering strips are formed of resilient sheet metal, preferably bronze, and so constructed and arranged that they extend in recesses 18 in said jambs 3 and bear upon said parting strips 6 in 90 weather-tight relation therewith from the top to the bottom of each sash. 85

However, altho I prefer to extend said weathering strips 15 in substantially parallel relation with the planes of the sash frames 12 and 13, they may be otherwise shaped, provided that they extend in sliding contact with some portion of the window jambs so as to seal the joints between the sashes and said jambs. 95 100

The weathering strips 15 on each of said sash 12 and 13 have slots 20 near the lower ends thereof for detachable connection with the ends of flexible connectors 21 respectively extending to spring drums 22; the upper ends of said connectors being detachably fitted in slots 24 in said drums. Said drums have square axial openings fitted upon squared portions 25 of the spring arbors 27 which are journaled, at their outer ends, in housing plates 28 and are journaled, intermediate of their length, in the bearing plates 29. Said drums are held upon said arbors 27 only by cotter pins 30 extending thru said arbors and said bearing plates 29 are detachably connected with the respective jambs, conveniently by screws 31. Each of said housing plates 28 is common to a pair of arbors and is detachably secured in the window frame, conveniently by screws 33, if the frame is wood, as indicated, but may be otherwise rigidly connected with the frame, if the latter is made of metal.

Between said bearing plates 29 and said housing plates 28, said arbors have axial slots 35 for engagement with the inner ends of respective sash counterbalance springs 36 which are evolutedly coiled around said arbors and have their outer ends secured to said housing plates by respective studs 37. Said springs may be adjusted to afford any desired tension upon the sash to counterbalance the weight of the latter, by winding their respective arbors when the drums are removed from the arbors; said drums being placed upon the arbors when the springs are at the proper tension.

It is to be understood that the construction and arrangement above described are such that said drums 22, with the flexible connectors 21 thereof, are rendered accessible by merely removing the cover plates 39 which are held in substantially flush relation with the inner faces of the jambs 3, conveniently by screws 40. Said cover plates may be removed whenever the sashes 12 and 13 are shifted to such position as to expose said plates. Upon the removal of said cover plates, the cotter pins 30 may be removed and the drums 22 slipped off their respective arbors 27. If it is desired to remove the springs, it is only necessary to remove the bearing plates 29; whereupon, the respective spring arbors and springs may be lifted out of the jamb. The inner ends of said arbors may be conveniently provided with slots 42 for engagement with a screw driver or similar tool, whereby the arbors may be turned to adjust the springs as aforesaid.

I also find it convenient to provide my improved windows with devices for preventing rattling of the sashes therein, and conveniently sheet metal springs 44 which are fitted in recesses 45 in the parting strips 6 in which they are held by removable sections

46 of said strips which are conveniently detachably secured by screws 47. Such springs 44 frictionally engage the weathering strips 15 on the sashes 12 and 13 and prevent rattling of the latter.

I find it convenient to form each of the sashes 12 and 13 with outer stiles 50 which are separable from the inner rectangular frames 51; said stiles being normally retained in sliding engagement with the jambs 3 aforesaid but the inner frames 51 being detachably connected with said stiles 50 by screws 53; so that the inner frames 51 may be glazed as indicated at 54 or similar frames 55 may be provided with insect screening, as indicated at 56; the glazed and screened frames 51 and 55 being interchangeable without removal of said outer stiles 50 from the jambs 3.

In order to insure that the inner sash frames aforesaid may be readily fitted in weather-tight relation with said outer stiles; I prefer to provide the contiguous faces 58 and 59 thereof with respective oppositely counterpart grooves 60 and 61 to receive the cylindrical weather strips 63 which extend across the spaces between said stiles and inner frames and may be secured to said stiles by nails 65, or may be otherwise held in operative position.

As above indicated; windows embodying my invention may be formed entirely of metal and, therefore, I do not desire to limit myself to the precise details of construction and arrangement herein set forth, as it is obvious that various modifications may be made therein without departing from the essential features of my invention, as defined in the appended claims.

I claim:

1. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; wherein the weathering strips have slots; and flexible connectors, comprising metal tapes, are respectively engaged at one end in said slots, and have their other ends extending around drums, in cooperative relation with means adapted to counterbalance said sash.

2. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are

- rendered water-proof; wherein the weathering strips have slots; and flexible connectors, comprising metal tapes, are respectively engaged at one end in said slots, and have their other ends extending around drums, in cooperative relation with means adapted to counterbalance said sash; including arbors extending axially from said drums and connected with respective springs tending to turn said drums. 6. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; having sash balancing means including rotary arbors journaled in said jambs, upon respectively opposite sides of the window; springs evolutedly coiled around said arbors, each connected at one end to one of said arbors and fastened at the other end in said jambs; drums on said arbors; and flexible connectors, each connected at one end to a drum, and extending around said drum to a sash. 3. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; having sash balancing means including rotary arbors journaled in said jambs, upon respectively opposite sides of the window; springs evolutedly coiled around said arbors, each connected at one end to a drum, and extending around said drum to a sash; each of said arbors being journaled in a bearing plate, detachably fixed in one of said jambs, between the spring and drum connected with that arbor. 4. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; having sash balancing means including rotary arbors journaled in said jambs, upon respectively opposite sides of the window; springs evolutedly coiled around said arbors, each connected at one end to one of said arbors and fastened at the other end in said jambs; drums on said arbors; and flexible connectors, each connected at one end to a drum, and extending around said drum to a sash; each of said arbors being journaled in a bearing plate, detachably fixed in one of said jambs, between the spring and drum connected with that arbor. 5. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; having sash balancing means including a metal housing plate at the outer portion of a jamb; a bearing plate intermediate of the thickness of said jamb; an arbor journaled in said housing and bearing plates and having a slot extending parallel with its axis between said plates; an evolutedly coiled spring of sheet metal having one end engaged in said arbor slot, between said plates, and the other end engaging a stud in fixed relation with said housing plate; said arbor having a polygonal portion extending inwardly from said bearing plate; a drum having an axial opening fitted for engagement with said arbor, and means for engaging the end of a flexible connector formed of sheet metal; the opposite end of said connector being attached to a sash. 6. A double-hung window including opposite jambs having sash slideways; and sash balancing means including a metal housing plate at the outer portion of a jamb; two bearing plates intermediate of the thickness of said jamb; two arbors respectively journaled at their outer ends in bearings in said housing plate, in spaced relation; said arbors being independently journaled in respective bearings in said bearing plates; springs between said plates, respectively encircling said arbors and tending to independently turn said arbors; drums on said arbors at the inward side of said bearing plates; and flexible connectors, each connected at one end to one of said drums, and extending around that drum to a sash; whereby, said sashes are independently balanced and said balancing springs are independently accessible by removal of the respective bearing plates. 7. In a window, the combination with a window frame including opposite jambs having respective sash slideways; of a pair of sash stiles fitted to slide in said ways; a pair of weathering strips of spring metal each having one edge rigidly connected with one of said stiles, and having its free edge in sliding contact with one of said jambs; whereby the joints between said frame and sash are rendered water-proof; sash balancing means in each of said jambs, including respective spring arbors journaled in said jambs with their axes parallel with the plane of said sash; springs tending to turn said arbors; and respective drums on said arbors each carrying a flexible connector extending therefrom to a sash. 8. A window as in claim 7; wherein the drums are adapted to fit said arbors in different positions of rotation; whereby the springs may be rotatably adjusted, to vary the tension thereof, by rotation of said arbors, before engagement of the drums with said arbors. 9. A window as in claim 7; wherein the arbors have slots respectively engaging one end of their springs and are polygonal at their portions adapted for engagement with the drums; whereby said drums may be connected with said arbors in different positions of the latter in accordance with different positions of adjustment of the springs, adapted to counterbalance sashes of different weights. 10. In a window, the combination with a window frame including opposite jambs having respective sash slideways; of a pair of sash stiles fitted to slide in said ways; a pair of weathering strips, of spring metal, each having one edge rigidly connected with one of said stiles, and having its free edge in sliding contact with one of said jambs; whereby the joints between said frame and sash are rendered water-proof; having sash balancing means including a metal housing plate at the outer portion of a jamb; a bearing plate intermediate of the thickness of said jamb; an arbor journaled in said housing and bearing plates and having a slot extending parallel with its axis between said plates; an evolutedly coiled spring of sheet metal having one end engaged in said arbor slot, between said plates, and the other end engaging a stud in fixed relation with said housing plate; said arbor having a polygonal portion extending inwardly from said bearing plate; a drum having an axial opening fitted for engagement with said arbor, and means for engaging the end of a flexible connector formed of sheet metal; the opposite end of said connector being attached to a sash. 11. A double-hung window including opposite jambs having sash slideways; and sash balancing means including a metal housing plate at the outer portion of a jamb; two bearing plates intermediate of the thickness of said jamb; two arbors respectively journaled at their outer ends in bearings in said housing plate, in spaced relation; said arbors being independently journaled in respective bearings in said bearing plates; springs between said plates, respectively encircling said arbors and tending to independently turn said arbors; drums on said arbors at the inward side of said bearing plates; and flexible connectors, each connected at one end to one of said drums, and extending around that drum to a sash; whereby, said sashes are independently balanced and said balancing springs are independently accessible by removal of the respective bearing plates. 12. In a window, the combination with a window frame including opposite jambs having respective sash slideways; of a pair of sash stiles fitted to slide in said ways; a pair of weathering strips of spring metal each having one edge rigidly connected with one of said stiles, and having its free edge in sliding contact with one of said jambs; whereby the joints between said frame and sash are rendered water-proof; sash balancing means in each of said jambs, including respective spring arbors journaled in said jambs with their axes parallel with the plane of said sash; springs tending to turn said arbors; and respective drums on said arbors each carrying a flexible connector extending therefrom to a sash. 13. A window as in claim 12; wherein the drums are adapted to fit said arbors in different positions of rotation; whereby the springs may be rotatably adjusted, to vary the tension thereof, by rotation of said arbors, before engagement of the drums with said arbors. 14. A window as in claim 12; wherein the arbors have slots respectively engaging one end of their springs and are polygonal at their portions adapted for engagement with the drums; whereby said drums may be connected with said arbors in different positions of the latter in accordance with different positions of adjustment of the springs, adapted to counterbalance sashes of different weights.

10. A window as in claim 6; wherein the drums are adapted to be fitted upon said arbors in different positions of rotation of said arbors and springs; whereby the stress of said springs upon said sashes may be independently adjustably varied.

11. In a window structure, the combination with a substantially plane strip of resilient metal substantially as long as the vertical extent of a window sash stile and having at one edge thereof means for detachable engagement with such stile and having at the opposite edge and near one end thereof means for engaging a flexible connector; of a flexible connector comprising a substantially plane metal tape adapted, at one end, for detachable connection with said strip by the attaching means of the latter; a drum attached to the opposite end of said tape and encircled by said tape; and sash counterbalancing means operatively connected with said tape drum, including a spring arbor in detachable coaxial relation with said drum and having its axis parallel with the plane of the window; a metal frame in which said spring arbor is journaled; and a spring formed of a normally plane strip of metal operatively engaged at its inner end with said arbor, evolutedly coiled around said arbor, and engaged at its outer end with said frame.

12. A window structure as in claim 11, adapted for a double-hung window and wherein said metal frame has journals at different heights for the different spring arbors provided with respective drums and springs; whereby said arbors are held in obliquely spaced relation with respect to the plane of the window, and are adapted for inclusion in a jamb of minimum width with springs which when coiled are of greater diameter than the width of the sash.

13. In a window structure; sash counterbalancing means adapted to be fitted in the window frame from the outer face of the window jamb, including a housing plate adapted to fit flush with the outer face of the jamb and extending in a plane transverse to the plane of the window, and having screw openings for detachable connection with the jamb, and a pair of stud screws extending inwardly from said housing plate, parallel with the plane of the window and having nuts at the inner ends thereof; and an arbor bearing intermediate of said pair of screws; and a spring terminal stud in eccentric relation with said arbor bearing; a bearing plate extending in parallel relation with said housing plate and operatively connected with the latter by said pair of screws and nuts, and having an arbor bearing intermediate thereof in coaxial relation with the arbor bearing in said housing plate; a spring arbor journaled in said arbor bearings, having a cylindrical portion fitted in said housing and bearing plates, and a squared portion extending

inwardly from said bearing plate; the axis of said arbor extending parallel with the plane of the window; a spring formed of a strip of primarily plane metal having its inner end engaged in a slot in said arbor and its outer end engaged on said housing plate stud; a cover plate having attaching means at opposite ends thereof and adapted to extend in parallel relation with said housing and bearing plates; a rotary drum detachably rigidly connected with the squared end of said arbor between said bearing plate and cover plate; and a flexible connector having its inner end connected with said drum and evolutedly coiled thereon; and having means at its outer end for detachable connection with a sash.

14. A window structure as in claim 13; wherein the means at the outer end of the spring for detachably connecting it with the sash is a metallic weathering strip having a slot engaging the end of the spring, and having screw openings for engagement with the sash.

15. A window structure as in claim 13; including two spring arbors and their appurtenances spaced in oblique relation with respect to the plane of the window and respectively adapted to register with an inner and an outer sash in a double-hung window.

16. Sash counterbalancing means including an outer housing plate, an intermediate bearing plate, and an inner cover plate in parallel spaced relation; a spring arbor journaled in said housing plate and bearing plate; a drum fixed on said spring arbor between said bearing plate and cover plate; a flexible connector evolutedly coiled on said drum and having its inner end connected to said drum and its outer end provided with means for detachably engaging a sash; and a spring evolutedly coiled on said arbor between said housing plate and bearing plate and having its inner end connected to said arbor and its outer end connected to said housing plate.

In testimony whereof, I have hereunto signed my name at Philadelphia, Pennsylvania, this 13th day of August, 1928.

DANIEL J. DUNBAR.
